United States Patent Office.

ISAAC T. CRUM, OF CHICAGO, ILLINOIS.

Letters Patent No. 62,014, dated February 12, 1867.

DEVICE FOR FORMING HORSE-COLLARS.

The Schedule referred to in these Letters Patent and making part of the same.

TO ALL WHOM IT MAY CONCERN:

Be it known that I, ISAAC T. CRUM, of Chicago, in the county of Cook, and State of Illinois, have invented a new and useful Form for Bending Rims for Horse-Collars; and I do hereby declare that the following is a full, clear, and exact description of the construction and operation of the same, reference being had to the annexed drawings and letters of reference marked thereon, making a part of this specification, in which—

Figure 1 is a plan view of my form, showing the position of the rim bent around it.

Figure 2 is a longitudinal elevation of the form, showing the position of the rim when being taken off of the same.

This invention relates to that in which blocks are used, having external forms to correspond with the internal shape which the wood when bent is to have; and its nature consists in the use of a form, made the required shape of the collar, and having flanges projecting outward from the lower part of the form for the purpose of holding the rim in position on the same when being bent; and further, in providing a standard, placed at a suitable distance from the top end of the form, for holding the rim on the form when and after being bent. By this arrangement a very convenient device is provided for bending rims for collars at small cost. When but little work is required to be done on the form, it may be made of wood, with metallic flanges and standard, but cast iron will be found the cheapest in the end, as the steam from the rim will not soften it like wood.

A represents the form, which may be made either of wood or metal, and of such shape as will best suit the neck of the horse. D shows flanges, projecting outward from the block far enough to prevent the rim from slipping off when being bent. When the form A is made of wood the flanges can be secured to it by means of the nails a, but when made of cast iron they can be cast solid with the form. H shows the shank of the standard C rigidly attached to the under side of the top of the form A by means of the screws ff. This shank and standard can also be cast solid with the form A when it is made of iron.

Operation.

B represents the rim after being bent on the form A. In order to bend the rim, one end, as seen at h, must be put between the standard C and the form A, after which the opposite end of the rim, as seen at L, can be forced around the form, lapped over the end K, and secured between the form and standard, as seen at fig. 1. B, fig. 2, shows how the rim may be forced downward so as to be taken off from the block without opening the ends L K.

Having thus fully described my device, what I claim, and desire to secure by Letters Patent of the United States, is—

The combination of the form A with the flanges D and standard C, substantially as set forth.

ISAAC T. CRUM.
